[57] CLAIM

The ornamental design for a trailer ramp, as shown and described.

DESCRIPTION

FIG. 1 is a front perspective view of a trailer ramp showing our new design;

FIG. 2 is a rear elevational view thereof;

FIG. 3 is a front elevational view thereof;

FIG. 4 is a right side elevational view thereof, the left side being a mirror image of the right;

FIG. 5 is a top plan view thereof;

FIG. 6 is a bottom plan view thereof;

FIG. 7 is a left side elevational view showing an alternate embodiment of our design;

FIG. 8 is a front elevational view thereof; and,

FIG. 9 is a rear elevational view thereof.

*Fig. 5**Fig. 6**Fig. 7**Fig. 8**Fig. 9*
